UNITED STATES PATENT OFFICE

WILLIAM C. CARTER, OF WELLSTON, MISSOURI

CARBURETOR

Application filed January 20, 1923. Serial No. 613,919.

This invention relates to carburetors for internal combustion engines.

One object of my invention is to provide an efficient carburetor of simple design, in which the air valve and the fuel valve are both controlled by a diaphragm.

Another object is to provide a carburetor of the general type referred to that is compact and inexpensive to manufacture.

10 Another object is to provide a carburetor that is equipped with a novel means of simple design for varying the proportion of air admitted to the air passageway or mixing chamber by the air valve.

15 Another object is to provide a carburetor that can be adjusted or regulated easily to vary the mixture produced by the carburetor by simply changing the position of a device that governs the suction created in a chamber provided with a movable element that controls the air valve and the means that admits liquid fuel to the air passageway of the carburetor.

20 And still another object is to provide a carburetor that is economical at ordinary running speeds and also well adapted for high speed work. Other objects and desirable features of my invention will be hereinafter pointed out.

25 Figure 1 of the drawings is a vertical longitudinal sectional view of my improved carburetor, showing the parts of same in the positions they occupy when the throttle valve is closed; and

30 Figure 2 is a vertical longitudinal sectional view of said carburetor, showing the throttle valve open.

I have herein illustrated my invention embodied in a carburetor of the side outlet type 35 that is adapted to be arranged at one side of the intake manifold of the engine with which the carburetor is used, but it will, of course, be obvious that it is immaterial how the carburetor is arranged with relation to 40 the intake manifold of the engine.

Briefly stated, my improved carburetor consists of a mixing chamber or air passageway A to which liquid fuel and air are supplied, a throttle valve B for governing the escape of the mixture from said mixing

chamber or passageway to the intake manifold of the engine on which the carburetor is used, an air valve C for governing the circulation of air through said passageway, a means, designated as an entirety by the reference character D, for admitting liquid fuel to said air passageway, and a diaphragm E for controlling the air valve C and the means D which admits fuel to the air passageway A. Various means may be used for admitting liquid fuel to the air passageway or mixing chamber A, but I prefer to use a means consisting of a fuel nozzle 1 arranged in the mixing chamber and provided with a fuel supply orifice 2 that is controlled by a needle valve 3 that is combined with the air valve C in such a way that said elements will move in unison, thereby causing the supply of air and the supply of liquid fuel to the mixing chamber to be governed by the diaphragm E. The diaphragm E is so constructed and arranged that when the throttle valve B is open the suction that is created in the mixing chamber at ordinary running speeds will be exerted on the diaphragm in such a way as to maintain the air valve C and the fuel valve 3 in such positions as to cause the proper proportions of air and liquid fuel to be supplied to the mixing chamber, and when said throttle valve is opened suddenly to accelerate the speed of the engine, the proportion of liquid fuel supplied to the mixing chamber will be increased sufficiently to produce a rich accelerating charge. I accomplish this desirable result by arranging the fuel supplying device D between the air valve C and the intake of the engine and by arranging the diaphragm E so that it forms one wall of a chamber F that is directly connected with the mixing chamber A by a duct 4 formed preferably in the stem 3^a of the fuel valve 3 and provided at its inner end with an orifice 4^a that is arranged in the mixing chamber, as shown in Figure 1, the opposite end of said duct 4 communicating with the chamber F of which the diaphragm forms one wall. An expansion spring 5 that is arranged in the chamber F normally exerts pressure on the diaphragm E in a direction tending to hold the air valve C and the fuel valve 3 in their closed

positions, but whenever a suction or partial vacuum is created in said chamber F by the suction produced in the mixing chamber, the diaphragm E will move in opposition to the spring 5, and thus open the air valve and the fuel valve.

Any suitable type of air valve C may be used, but I prefer to use a substantially disk-shaped valve that is rigidly connected to the stem 3^a of the fuel valve and which is so arranged that it seats against a valve seat 6 at the inlet end of the portion of the main air passageway that constitutes the mixing chamber wherein the liquid fuel is mixed with the air. In view of the fact that the suction in the mixing chamber is exerted on the air valve C in a direction tending to hold it seated and said air valve is moved into its open position by causing the suction in the mixing chamber to be exerted on the diaphragm E in an opposite direction, it is essential that said diaphragm be of considerably greater diameter than the air valve. Therefore, it is desirable to make the air valve as small as possible, so as to overcome the necessity of using an abnormally large diaphragm. I accomplish this by using an air passageway A of the Venturi type, provided intermediate its inlet and outlet with means for speeding up the air traveling through said passageway. In the form of my invention herein illustrated the means just referred to consists of a contracted, reduced or tapered air inlet that increases the suction at the inlet of the mixing chamber sufficiently to compensate for the reduced diameter of said inlet, and thus causes practically the same quantity of air to be drawn into said mixing chamber when the air valve is open as if said chamber were of uniform diameter throughout its entire length.

When the throttle valve is closed, as shown in Figure 1, the air valve C will bear against the valve seat 6, thus closing the inlet of the mixing chamber A, and the needle valve 3 will project into the discharge orifice 2 of the fuel nozzle 1 to such an extent as to nearly close said orifice. At ordinary running speeds, when the throttle valve is open, as shown in Figure 2, the suction in the mixing chamber F causes air to be sucked out of the chamber F through the duct 4, thereby exerting a pull on the diaphragm in a direction tending to flex it to the left, and thus causing the air valve C and the fuel valve 3 to be maintained in such positions that air and liquid fuel will be admitted to the mixing chamber in proper proportions to produce a combustible mixture suitable for ordinary running speeds. As the position of the throttle valve is changed gradually to vary the speed of the engine, the suction in the chamber A will vary, thereby causing the diaphragm to vibrate and open and close the air valve C and fuel valve 3 more or less, so as to vary the supply of air and fuel to the mixing chamber

without changing the relative proportions of fuel and air. If the throttle valve is opened suddenly, however, to accelerate the speed of the engine, the proportion of liquid fuel admitted to the mixing chamber will be increased abnormally, due to the fact that the duct 4 which establishes communication between the diaphragm chamber F and the mixing chamber A is not of sufficient cross-sectional area to cause the air to be exhausted from the chamber F rapidly enough to cause the air valve C to open quickly. In other words, as the opening movement of the air valve C is effected by sucking air out of the diaphragm chamber F through a restricted opening or small orifice 4^a in the duct 4, a sudden increase in the intensity of the suction in the mixing chamber A, produced by opening the throttle valve suddenly, results in a large quantity of fuel being drawn out of the fuel supply orifice 2, but it does not result in a proportionally great quantity of air being drawn into the mixing chamber past the air valve C, because the air cannot escape from the diaphragm chamber F through the duct 4 rapidly enough to compensate for the increased suction in the mixing chamber and permit the air valve to open quickly. It will thus be seen that while the proportions of fuel and air will remain practically constant, at ordinary running speeds when the throttle valve is moved gradually to vary the speed of the engine, a sudden opening of the throttle valve to accelerate the speed of the engine causes the high suction which is then created in the mixing chamber to be exerted directly on the liquid fuel supplying device, with the result that a rich starting charge will be admitted to the mixing chamber.

The proportion of air admitted to the mixing chamber by the air valve C can be changed in various ways, but preferably by changing the position of said air valve relatively to its seat 6. In the form of my invention herein illustrated the valve seat 6 is constructed in such a way that the position of same relative to the air valve can be changed to increase or diminish the proportion of the air supply at any speed of the engine. One convenient way of accomplishing this is to form the valve seat 6 on an adjustable member G that can be moved longitudinally of the direction of movement of the air valve C, said member G being of tapered form and constituting the reduced air inlet of the mixing chamber A. When the member G is set in its extreme position to the right the air valve C will be spaced farther away from the valve seat 6 when the diaphragm flexes to the left, due to the suction in the mixing chamber, thus causing a relatively large quantity of air to be admitted to the mixing chamber, and when said member G is set in its extreme position to the left, a relatively small amount of air will be admitted to the mixing chamber when the dia-

phragm flexes to the left under the influence of the suction in the mixing chamber, due, of course, to the fact that the air valve is then spaced comparatively close to the valve seat 5. It is immaterial what means is used to adjust or change the position of the member G, but I prefer to provide said member with an externally screw-threaded portion 7 that is screwed into the part H of the carburetor 10 that constitutes the mixing chamber A, and equip said member G with an arm 8 to which an operating device (not shown) is adapted to be connected. When the member G is rotated in one direction the externally screw-threaded portion 7 thereon will cause it to 15 move to the right, thus increasing the proportion of the air supply, and when said member is rotated in the opposite direction, the screw-threaded portion 7 thereon causes 20 it to move to the left, thus decreasing the proportion of the air supply.

Another feature of my invention which I believe to be novel, is providing a carburetor of the type in which the supply of air and 25 liquid fuel to the air passageway is controlled by an element governed by the suction in said passageway, with a device that can be adjusted or operated so as to modify or vary the suction produced on said element by the 30 suction in the mixing chamber. The device just referred to can be constructed and arranged in various ways, but in its simplest form it will consist of a valve that controls either an air inlet or an air outlet to a chamber 35 equipped with a movable element that actuates the air valve and the fuel valve. In the carburetor herein shown the movable element just referred to is formed by the dia- 40 phragm E and the diaphragm chamber F is provided with a valve I that controls an air admission port 9 which leads to said chamber. If it is desired to diminish the supply 45 of air to the mixing chamber A when the engine is in operation, the valve I can be ad- justed so as to partially open the air inlet port 9 leading to the diaphragm chamber F, there- 50 by reducing the suction that is created in said chamber by sucking air out of said chamber through the duct 4, and consequently, reduc- 55 ing the degree of movement of the air valve C under the influence of the suction in the mixing chamber. The chief function of the valve I, however, is to choke the air valve C or hold said valve in its closed position, so 60 as to produce a rich starting charge. Nor- mally, the valve I is set in such a position as to close the air inlet port 9, as shown in Figure 2, but if it is desired to produce a rich starting charge, said valve is moved into a 65 position to open the air inlet port 9, as shown in Figure 1. When said valve I is set in the position last referred to the act of opening the throttle valve will not cause the air valve to open, due, of course, to the fact that the 70 diaphragm chamber F is then in direct com-

munication with the atmosphere. Conse- 75 quently, the suction in the mixing chamber A will cause liquid fuel to be drawn out of the orifice 2 in the fuel nozzle 1, and will cause a small quantity of air to be drawn into the mixing chamber through the duct 4 and ori- 80 fice 4^a, previously described, the air valve C being held seated at such times by the expansive force of the spring 5. So far as this feature of my invention is concerned, it is 85 immaterial what type or kind of movable element is used for controlling the air valve and the means that admits liquid fuel to the main air passageway, so long as said element consists of a movable device combined with a 90 chamber which in turn is connected with the air passageway of the carburetor in such a manner that the suction in said passageway is exerted on said device in a manner tending to change the position of same. 95

For economy in operation at low speeds it is essential that the liquid fuel be split up into fine particles before it enters the intake mani- 100 fold of the engine, but when high speed and power are desired and economy in the con- sumption of fuel is not a factor, better results are obtained if the liquid fuel is not split up or divided into as small particles as possible before it enters the intake manifold of the en- gine. All prior carburetors with which I am 105 familiar are constructed either in such a way that they will be economical in the consump- tion of fuel but not particularly well adapted for high speed work, or constructed in such a way that they will be particularly well adapt- 110 ed for high speed work but will be uneconomical in the consumption of fuel at low speeds. One object of my invention is to provide a carburetor, which, in addition to being eco- nomical in the consumption of fuel at low 115 speeds, is also well adapted for high speed work.

To obtain such a carburetor I arrange the throttle valve B between the fuel supplying means and the intake of the engine and ar- range one or more auxiliary throttle valves B' in tandem relation with said throttle valve B and operatively connect said auxiliary valve or valves with the throttle valve by a link 10 or other means connected to arms 11 115 on the stems of said valves. Preferably, the auxiliary throttle valve B' is of the same diameter as the main throttle valve B. At ordinary running speeds, when the throttle valves B and B' are partly open, the liquid 120 fuel in the mixture will be divided into mi- nute particles, by reason of having to pass several times through contracted openings, to wit, the annular openings between the pe- 125 ripheral edges of the throttle valves and the side wall of the passageway in which said valves are arranged, but when the throttle valves B and B' are wide open, the mixture can travel from the mixing chamber A into the intake manifold of the engine without 130

having to pass numerous times through contracted openings. The result is that the liquid fuel in the mixture will not be split up or divided into small particles when the throttle valve is wide open, thus making the carburetor particularly well adapted for high speed work on account of the fact that the fuel in the mixture enters the intake manifold of the engine in a practically raw state.

10 At low speeds, when the throttle valve is partly closed, the liquid fuel in the mixture will be torn up into fine particles before entering the intake manifold, thereby making the carburetor economical in the consumption of fuel at ordinary running speeds.

15 Any suitable means can be used for supplying liquid fuel to the fuel passageway in the nozzle 1, such as a conventional float chamber J, and the mixing chamber or passageway A can be formed by a tubular member H provided at one end with a flange H' by which it can be attached to the intake manifold of the engine and provided at its opposite end with a hollow portion H² having 20 an air intake 12 at its upper end. The diaphragm E is preferably formed by a piece of impervious fabric or a laminated structure composed of several thicknesses of flexible material, and said diaphragm is arranged in 25 side of the hollow portion H² of the member H and secured to a ring-shaped part 13 on said portion by a plate 14 of substantially concavo-convex shape that forms the rigid wall of the diaphragm chamber F, said plate 30 having a cup-shaped part 15 thereon in which the spring 5 is seated. The air valve C is integrally connected to a sleeve 16 into which the stem 3^a of the fuel valve is screwed, and said sleeve is provided with a flange 17 that 35 co-operates with a head 18 on the stem of the fuel valve to clamp the diaphragm E to said valve stem, a wear plate 19 being preferably interposed between the diaphragm and the head on said valve stem, so as to form a 40 seat for the spring 5, and thus prevent said spring from cutting the diaphragm.

45 Having thus described my invention, what I claim as new and desire to secure by Letters Patent is:

50 1. A carburetor provided with a passageway, a manually-operable throttle valve for governing the escape of the mixture from said passageway to the intake of the engine, an air valve arranged between the throttle 55 valve and the air intake to said passageway for admitting air to said passageway, a fuel port in said passageway for admitting fuel to same, a fuel valve for governing the admission of fuel from said port to said passageway, connected with said air valve so as to 60 move in unison with the same and arranged between the air valve and the throttle valve, a chamber provided with a diaphragm that is connected with said air valve and fuel valve 65 so as to control said valves, and a duct leading

from said diaphragm chamber and communicating with said passageway at a point between the air valve and the throttle valve, whereby a quick movement of the throttle valve into its open position closes the air valve and momentarily produces a high suction on the fuel supply port in said passageway, said suction thereafter diminishing while the pressure in the diaphragm chamber is balancing with the pressure in said passageway.

2. A carburetor provided with a passageway, a manually-operable throttle valve for governing the escape of the mixture from said passageway to the intake of the engine, an air valve arranged between the throttle valve and the air intake to said passageway for admitting air to said passageway, a fuel port in said passageway for admitting fuel to same, a fuel valve for governing the admission of fuel from said port to said passageway, connected with said air valve so as to move in unison with the same and arranged between the air valve and the throttle valve, a chamber provided with a diaphragm that is connected with said air valve and fuel valve so as to control said valves, a duct leading from said diaphragm chamber and communicating with said passageway at a point between the air valve and the throttle valve, whereby a quick movement of the throttle valve into its open position closes the air valve and momentarily produces a high suction on the fuel supply port in said passageway, said suction thereafter diminishing while the pressure in the diaphragm chamber is balancing with the pressure in said passageway.

3. A carburetor provided with a passageway, a manually-operable throttle valve for governing the escape of the mixture from said passageway to the intake of the engine, an air valve arranged between the throttle valve and the air intake to said passageway for admitting air to said passageway, a fuel port in said passageway for admitting fuel to same, a fuel valve for governing the admission of fuel from said port to said passageway, connected with said air valve so as to move in unison with the same and arranged between the air valve and the throttle valve, a chamber provided with a diaphragm that is connected with said air valve and fuel valve so as to control said valves, a duct leading from said diaphragm chamber and communicating with said passageway at a point between the air valve and the throttle valve, whereby a quick movement of the throttle valve into its open position closes the air

valve and momentarily produces a high suction on the fuel supply port in said passageway, said suction thereafter diminishing while the pressure in the diaphragm chamber is balancing with the pressure in said passageway, a seat for said air valve, and means for bodily moving said valve seat longitudinally of the direction of movement of the air valve so as to change the relative position of said valve and valve seat and thus vary the resistance offered to the air that is drawn into said passageway.

WILLIAM C. CARTER.
